ABSTRACT

A hydraulic coupling is provided with a pick-up compartment directly connected with the working compartment and a reservoir compartment. The flow of liquid from the working compartment to the reservoir compartment and the quantities of liquid retained in the respective compartments are controlled by two simultaneously operated valve means in each compartment. Preferably, the valve means comprise pairs of slotted valve plates movable in close face contact with one another.

HYDRAULIC COUPLINGS

FIELD OF THE INVENTION

This invention is concerned with improvements in or relating to hydraulic couplings, of the kind comprising a pump element and a turbine element (sometimes known respectively as an impeller element and a runner element), each provided with a plurality of radially extending vortex-producing vanes. The interiors of the elements together form a working chamber containing a quantity of working liquid, usually an oil, and the two elements are coupled together for the transmission of torque between them by liquid vortices that are established in the working chamber between the said vanes. The invention is especially concerned with such couplings in which means are provided for varying the degree of filling of the said working chamber to vary the torque and power transmission capacity of the coupling.

REVIEW OF PRIOR ART

Hydraulic couplings are commonly employed in power transmission systems between a prime mover, such as an internal combustion engine or an electric motor, and a load to be driven by the prime mover. In an ideal arrangement the torque transmitted by the coupling is negligible while the prime mover is idling and increases smoothly and progressively to a maximum when the prime mover reaches its designed optimum speed range.

DEFINITION OF THE INVENTION

It is an object of the present invention to provide a new hydraulic coupling of this type.

According to the present invention there is provided a new hydraulic coupling comprising a radially vaned pump element and a radially vaned turbine element together defining a toroidal working chamber, a reservoir chamber rotatable with the pump element, partition means in the interior of the reservoir chamber dividing the interior thereof to provide at least a pick-up compartment communicating with the working chamber and a reservoir compartment, duct means connecting the pick-up and reservoir compartments for flow of liquid between them, first control means for controlling the quantity of liquid in the pick-up compartment, second control means for controlling the quantity of liquid in the reservoir compartment, and means connecting said first and second control means for simultaneous operation whereby operation of the first control means to reduce the quantity of working liquid retained in the pick-up compartment and to deliver it to the reservoir compartment is accompanied by operation of the second control means to increase the quantity of working liquid retained in the reservoir compartment, and vice versa.

DESCRIPTION OF THE DRAWINGS

A hydraulic coupling which is a particular preferred embodiment of the invention will now be described, by way of example, with reference to the accompanying diagrammatic drawings, wherein

FIG. 1 is a cross-section through the said embodiment, taken on the longitudinal axis thereof.

FIGS. 2A and 2B show the relative position of the first and second control means of the coupling when they are set for the coupling to transmit maximum power, the views being taken in the direction of the arrows A and B respectively in FIG. 1.

FIGS. 3A and 3B show the relative positions for an intermediate power setting, and

FIGS. 4A and 4B show the relative position when they are set for the coupling to transmit minimum power, e.g., when the working circuit is empty.

DESCRIPTION OF PREFERRED EMBODIMENTS

The coupling illustrated diagrammatically herein comprises a pump element 10 mounted on a power input shaft 11 that is adapted to be connected to a prime mover, such as an internal

combustion engine or an electric motor, and a turbine element 12 mounted on a power output shaft 13, that is adapted to be connected to apparatus to be driven via the coupling. The immediately adjacent inner ends of the two shafts 11 and 13 are 5 mutually supported by a single ball bearing 14, the inner bearing race being mounted on a spigot on the end of the shaft 13 while the outer bearing race is mounted in a bore in the shaft 11, the two coupling elements being rotatable about a common longitudinal axis. The interiors of the two elements constitute respectively a pump chamber and a turbine chamber, these two chambers together forming the usual toroidal-shaped working chamber which contains a quantity of working liquid, usually an oil. Each chamber is provided with the usual radially extending, vortex-producing vanes 15 and 16 respectively.

The whole coupling is enclosed in a cylindrical casing 17 having a radial flange 18 at one end, by which the casing can be mounted on the corresponding portion of the engine with 20 which it is employed. The shaft 13 extends through the other end of the casing and is supported adjacent the end by two spaced bearings 19. The outer races of the bearings 19 are mounted against the inner face of an axial bore provided by a longitudinal tubular sleeve member 20 rigid with the casing 25 17, surrounding the shaft 13 within the coupling and extending toward the turbine element 12. A tubular control sleeve 21 is mounted on the sleeve 20 and is rotatable relative thereto under the control of an operator by means of a radial arm 22 and an axial extension 23, the latter extending through an ar- 30 cuate slot 24 provided in the end of the casing 17.

An extension 25 of the pump element 10 surrounds the turbine element in known manner to retain the working liquid in the coupling, a sealed bearing 26 providing a rotatable, fluid-tight joint between the extension and the adjacent end of the sleeve 21. The extension constitutes a reservoir member carried by the pump element, the interior of the reservoir being divided by a radially extending partition 27 into a pick-up compartment 28 immediately adjacent the coupling working circuit and a reservoir compartment 29 between the partition and the end of the extension 25. The partition is carried by 35 and is rotatable with the extension.

The two compartments 28 and 29 are provided with respective control means 30 and 31 for control of the liquid level in 45 the respective compartment. The first control means comprise two radially extending parallel partitions 32 mounted on the sleeve 20 and joined at their radially outer edges by a cylindrical wall 33 to form, in effect an annular chamber. Two co-operating radially extending parallel partitions 34 are mounted on the sleeve 21 and extend therefrom in close face contact with the partitions 32 to form respective control valves therewith. The partitions 34 are joined at their outer ends by a cylindrical wall 35 and they form, in effect an annular chamber 36 within the chamber formed by the partitions 32. The partitions are provided with valve slots which will be 50 described in detail hereinafter.

The second control means comprise two radially extending parallel partitions 37 carried by the sleeve 20, and two co-operating partitions 39 carried by the sleeve 21, the respective annular chambers being completed by end walls 38 and 40, and the inner chamber being given the reference 41. It will be 55 seen that rotation of the sleeve 21 relative to the sleeve 20 will rotate the partitions 34 and 39 simultaneously in the said face contact with one another to give simultaneous operation of the first and second control means. The interiors of the two chambers 36 and 41 are in permanent communication with one another via co-operating openings 42 in the partition and passageways 43 in a hub 44 joining the adjacent partitions 32 and 37, the hub being provided with radial openings 45. The provision of two pairs of relatively movable partitions arranged in the manner illustrated to feed liquid in opposite directions into a centrally located chamber provides a balance 60 of forces that minimize the resultant forces applied to the sleeves 20 and 21.

Referring now to FIGS. 2A each partition 32 of the first control means is provided with a single radially-extending elongated opening 46, while each co-operating partition 34 is provided with a small radially-outer bleed opening 47, a radially extending, elongated full-open opening 48 and an elongated control opening 49, the last-mounted opening being suitably inclined to the radial. Similarly, each partition 37 of the second control means is provided with a single radially extending elongated opening 50, while each co-operating partition 39 is provided with a radially extending, elongated full-open opening 51 and an elongated control opening 52, the latter being suitably inclined to the radial.

In operation of the device the extension 23 is placed by the operator, e.g., via a suitable control linkage, in the one extreme position corresponding to the coupling providing maximum power transmission capacity, whereby the two control members are in the relative positions illustrated by FIGS. 2A and 2B. The openings 46 and 47 register with one another so that there is a "bleed" flow of the working liquid from the pick-up compartment 28 into the stationary chamber 36 as indicated by arrow 53. This liquid can flow via openings 42 and the respective channels 43 into the reservoir chamber and ensures that there is a small amount of fluid circulating between the working circuit and the reservoir 29 for analogizing control. At this time the two openings 50 and 51 are in full register with one another and any liquid entering the reservoir, other than the small amount permanently therein against the inner wall of the extension 25 is immediately returned to the pick-up compartment and the working circuit via the respective bores 42, etc., as indicated by the arrows 54.

If the control member is now moved to the other extreme position, corresponding to no power transmission, then the full-open opening 48 registers with the openings 46 and there is a maximum flow of working liquid from the pick-up compartment to the reservoir compartment. At the same time the openings 50 are fully closed and all liquid that enters the reservoir compartment must remain therein, emptying the working circuit. With the control member in this position the engine may run at any speed from idle to full r.p.m. without transmission of power through the coupling.

If the control member is placed at an intermediate position illustrated by FIGS. 3A and 3B, then simultaneously the opening 46 registers with a part of the inclined control opening 49, while the opening 50 registers with a corresponding part of the inclined control opening 52. The quantities of liquid in the two compartments will depend upon the radial distance from the coupling axis at which the co-operating slots intersect one another to provide corresponding openings for the passage of the working liquid in the respective flow paths. A smooth and progressive control of the coupling power output can thus be ensured by adjustment of the characteristic constituted by the

angle of rotation of the control member plotted against the radial distances of the respective opening intersections, which in turn corresponds to the radial depth of the liquid in each compartment and the corresponding volumes thereof. Thus, although for convenience in illustration in a diagrammatic drawing the elongated openings are shown as straight and of uniform width along their length, in other embodiments they may be suitably curved and of varying shape along their length to achieve the desired characteristic.

10 In another embodiment which is not specifically illustrated the various control openings are provided in the co-operating pairs of end walls 33, 35 and 38, 40 instead of the side partition walls to achieve the same technical effect.

What is claimed is:

- 15 1. A new hydraulic coupling comprising a radially vanned pump element and a radially vanned turbine element together defining a toroidal working chamber, a reservoir chamber rotatable with the pump element, partition means in the interior of the reservoir chamber dividing the interior thereof to provide at least a pick-up compartment communicating with the working chamber and a reservoir compartment, duct means connecting the pick-up and reservoir compartments for flow of liquid between them, first control means for controlling the quantity of liquid in the pick-up compartment, 20 second control means for controlling the quantity of liquid in the reservoir compartment, and means connecting said first and second control means for simultaneous operation whereby operation of the first control means to reduce the quantity of working liquid retained in the pick-up compartment and to deliver it to the reservoir compartment is accompanied by operation of the second control means to increase the quantity of working liquid retained in the reservoir compartment, and vice-versa.

2. A coupling as claimed in claim 1, wherein each control 35 means comprises a pair of slotted members mounted coaxially with the coupling and rotatable relative to one another to control the flow of working liquid therethrough.

3. A coupling as claimed in claim 2, wherein each control 40 means comprises a pair of flat, slotted, annular plate members movably mounted in close face contact with one another and forming a respective plate valve.

4. A coupling as claimed in claim 2, wherein each control 45 means comprises two spaced pairs of slotted members operated by a common control means and feeding working liquid in opposite directions to minimize the resultant forces applied to the said control means.

5. A coupling as claimed in claim 3, wherein each control 50 means comprises two spaced pairs of slotted members operated by a common control means and feeding working liquid in opposite directions to minimize the resultant forces applied to the said control means.
